OPEN-END METAL BENDING BRAKE

Robert L. Webb, Imperial, Pa.

Application April 22, 1948, Serial No. 22,518

9 Claims. (Cl. 153—16)

1

This invention relates to metal bending machines, and particularly, to open-ended sheet metal bending brakes.

Metal bending brakes, in general, include a bedplate and clamping beam between which a sheet of metal to be bent is inserted and clamped preparatory to the bending, the actual bending being accomplished by swinging a bending beam upwardly against a portion of the metal overhanging it. Normally, the clamping beam is secured to the bedplate by bolts, or the like, which extend through the end portions of the beam and are anchored in the bedplate. With such brakes, it is apparent that the metal to be bent must be inserted wholly between the bolts at the ends of the beam and, for this reason, these brakes are limited in the types of bends which they are capable of making. For example, it is not possible to bend one portion only of a length of sheet, because to do so that portion must be clamped between the beam and the plate while the remaining portion must lie outside of the beam. Another bending limitation of this "closed-end" type of brakes is that either they are incapable of forming boxes or, if adapted for such work, the box when formed, will be caught between the beam securing bolts and can not be removed without first removing the bolts.

To permit a wide variety of bends a type of brake, called an "open-end" brake, has been attempted, such brakes being characterized by the fact that there is a substantial length of clamping beam between each securing bolt and its end of the beam, and the space between this length and the bedplate is unobstructed by bolts, or the like, so that a portion of a length of sheet metal can be inserted therein while the remainder of the length can lie beyond the clamping beam. The difficulty with such open-end brakes, and the reason that all attempts to provide such, so far as is known, have been failures, is that, when this space is left unobstructed, no practical way has been found to reinforce the extreme end portions of the clamping beam. Consequently, during a bending operation these ends tend to spring upwardly and float rearwardly and unsatisfactory bends are formed.

It is therefore an object of this invention to provide an open-end brake in which the ends of the clamping beam rigidly clamp the metal and do not spring or float during the bending.

Other objects are to provide a rigid, open-end brake which is inexpensive to manufacture, sufficiently light to be portable, strong enough to handle commonly used metal gauges, capable of

making sharp bends, and which can be operated quickly and easily to make an unusually large variety of bends.

According to the invention, the brake includes a bedplate and a clamping beam, between which sheet metal is clamped and a bending beam adapted to be swung upwardly to bend the metal against the edge of the clamping beam. Normally the clamping beam is urged away from the bedplate by a spring, or other suitable means, and cam mechanism is provided to overcome the spring and press the beam against the plate to clamp inserted metal. The cam mechanism includes a beam securing member which, preferably, is a bolt anchored in the bedplate and extending vertically upwardly through an opening provided centrally in the plate. Most suitably, a pair of cam mechanisms are provided which are carried by the bolts at set distances from the center of the clamping beam. Also, the cam mechanism includes a pair of slidably contacted discs each of which are provided with an opening through which the securing bolts extend, these discs being disposed between the cam of the cam mechanism and the bedplate and operating to distribute cam pressure evenly to the beam as well as to take up forces acting on the beam securing bolt. The openings both through the discs and the clamping beam are made larger than the beam securing bolt so that the beam is permitted to ride up and down, or reciprocate, with respect to it. The brake provided, therefore, is open-ended since there is an unobstructed space between the securing bolts and the ends of the clamping beam and metal can lie both within and without this space. The difficulty previously experienced with the springing and floating of the ends of such brakes is avoided by the use of fulcrum members, which preferably are blocks secured to the rear edge of the clamping beam inwardly of the cam mechanism and projecting downwardly from the beam toward the bedplate. When, as in the preferred form, the brake employs a pair of cam mechanisms, a pair of fulcrum blocks are provided, each being spaced inwardly from one of the cam mechanism bolts a set distance, this distance depending upon the characteristics of the metal from which the clamping beam is fabricated.

In operation, when the pressure of the cam mechanism is applied, the clamping beam first is moved to bring its working edge into initial contact with the metal. Preferably, the clamping beam is provided with a beveled working edge and this edge is rocked into its initial contact by

the fulcrum blocks. Subsequent pressure of the cam mechanism then operates to bow or arch the clamping beam around the fulcrum block and also to firmly press down the central portion of the beam, so that the full length of the beam tightly clamps the metal against the bedplate. The bowing of the beam around the blocks throws a large portion of the cam pressure into its extreme ends so that, when the metal is bent against the beam, the ends are sufficiently rigid to hold their position and, consequently, they will not rise up or float rearwardly.

The invention also contemplates means for selectively positioning the clamping beam with regard to the gauge of the metal to be bent, as well as certain strengthening members for the bedplate and bending beam, all of which will be described later with reference to the drawings.

The preferred embodiment of the invention is illustrated in the accompanying drawings of which Fig. 1 is a front elevation of the brake; Fig. 2 a rear elevation showing a sheet of metal inserted in one end of the brake and clamped preparatory to bending; Fig. 3 a section along line III—III of Fig. 1; and Fig. 4 a section similar to that of Fig. 3, but showing the position of the various parts during bending.

Referring to the drawings, the brake includes a bedplate 1 to which a clamping beam 2 is secured by means of a pair of cam mechanisms 3 and 4. This beam is considerably shorter than the plate and is provided with a front beveled edge 6 against which metal inserted between the beam and plate is bent, the bending being done by a bending beam 7 which is pivotally attached to the bedplate by hinges 8, the beam also being provided with a pair of handles 9 by which it can be swung upwardly to bend the metal. In order to provide the brake with sufficient strength and rigidity for bending metal of normal gauges, the bedplate and clamping beam are reinforced by angles 11 and 12 (Fig. 3) and by rods 13 and 14 (Fig. 1), the rods both having adjustable members 16 and 17 to vary their tension. The brake as a whole is supported on a support 20 which, preferably, is detachably connected to the bedplate so that the support and the brake can be separated and each part easily carried.

When the brake is not in use, its clamping beam is automatically raised clear of the bedplate by a pair of coil springs 18 and 19, the ends of which are received in holes provided in the plate and the beam. Previously mentioned cam mechanisms 2 and 3 provide the force for clamping the metal to be bent, each of these including a securing member or bolt 21 anchored in the bedplate and extending vertically upwardly from it through an opening 22 provided near the center of the clamping beam. Preferably, a lug 23 is welded or otherwise secured to the under side of the bedplate to provide additional rigidity for the cam bolt. The portion of the bolt extending above the clamping beam is enlarged to receive a pivot pin 26 each end of which supports a cam 27, the cam being provided with an operating handle 28. Between the cam and the upper surface of the clamping beam are positioned a pair of slidably contacted discs 31 and 32, the lower surface of the upper disc being convex and the lower disc having a matching concave upper surface. The cam, of course, exerts its pressure through the discs to the clamping beam, the discs being provided to evenly distribute the cam pressure to the beam, as well as, to take up forces which other-

wise would tend to bend the cam bolt, all as will be described later in greater detail.

From the description so far, it can be recognized that the brake provided is an open-end type since the spaces between bolts 21 and the extreme ends of the clamping beam are unobstructed. As mentioned before, the principal difficulty with such open-end brakes is that these extreme ends have a tendency to spring and float during the bending operation. This invention avoids such by providing a pair of fulcrum members or blocks 33, these blocks, preferably, being bolted to the rear side of the clamping beam and have a lower rearwardly beveled portion 34 projecting downwardly from the bottom surface of the beam toward the bedplate. Further, the blocks each are positioned a spaced distance inwardly from beam-securing bolts 21, this distance depending upon the characteristics of the metal from which the clamping beam is fabricated.

The general purpose of each block 33 is to provide a fulcrum about which the clamping beam can be bowed or arched upon application of cam pressure, and for the purpose of reducing the pressure necessary to so arch the beam, it is preferred to initially provide the beam with a slight downward bow. The function of the blocks and the results of bowing the clamping beam can be understood best from a description of a bending operation, which is begun by inserting the metal and swinging the cam handles downwardly to exert pressure against the clamping beam. Although both of the cam mechanisms can be operated simultaneously, it usually will be preferred to use one of them at a time since this type of brake is adapted to make a certain bend at one end of the brake after which the metal is transferred to the other end where another bend is made. In describing the operation, the results of the applied cam pressure will be considered in a step-by-step progression until the metal is finally clamped, although of course, the actual application of pressure is by a smooth and continuous downward swing of the cam handles. Upon the application of the initial pressure, beveled projection 34 of the fulcrum block is brought into contact with the upper surface of the plate. Further pressure then causes the clamping beam to tilt or rock forwardly on its rounded tip into the position shown in Fig. 4, in which the extreme ends of the clamping beam contact the inserted metal while the central portion of the beam is clear of the metal by a slight fraction of an inch. To permit the beam to rock forward in this manner, openings 22 through which beam securing bolts 21 extend, as well as the beam openings through cam discs, are made larger than the bolts and also are inclined at an angle (Fig. 3), from the vertical axis of the bolt, this rocking action being shown in Figs. 3 and 4. With the beam so engaged, additional clamping force exerts a pressure which bows the rear portion of the beam over the fulcrum block and also forces the central portion of the beveled edge of the beam downward into tight clamping contact with the inserted metal. The bowing of the beam operates to throw a considerable portion of the downward force of the cam pressure into the end portions of the beam, this force, at least, being sufficient to maintain the rigidity of the beam during the bending operation and resist tendencies to spring. The exact forces which are set up in the clamping beam when it is bowed and bent around the rearward portion of the fulcrum blocks can only be surmised, but from observa-

tion of a brake in operation it appears that, in addition to the downward force, certain forwardly acting torsional forces are set up which hold the ends of the beam forwardly and resist floating.

As previously stated, the cam mechanisms each includes a pair of slidably contacting discs 31 and 32 which are especially useful in an open-end brake which is bowed in the manner taught herein. Their use will be appreciated better if it be considered that, should the cams act directly against the clamping beam instead of through these discs, the rocking movement of the beam into clamping engagement with the metal would exert a great pressure against the bolts which eventually would bend them. With the discs positioned as they are, this force is taken up by the sliding of one disc over the other in the manner indicated in Fig. 4. Also, this sliding causes cam pressure to be transmitted vertically to the beam and distributes the pressure evenly over the beam.

The invention also contemplates means to initially position the clamping beam in the most desirable position for bending any particular gauge of sheet metal. Such members consist of two pairs of set screws, each pair having a front and a rear screw 38 and 39 threaded into transverse openings provided in the clamping beam. As can be noted in Figs. 3 or 4, the screws project inwardly toward the clamping beam securing bolts so that, when tightened, they will move the clamping beam laterally with respect to the bolt. Assuming then that it is desired to bend 20 gauge sheet metal, the clamping beam first is set upon the bedplate, the rear screws 39 tightened against the bolts a sufficient amount to move the front beveled edge of the beam into exact alignment with the front of the bedplate and front screws 38 then brought just into contact with the bolts. The next operation is to unscrew the front bolts an amount equal to the thickness of 20 gauge metal, this operation leaving a space between the front edge of the bolt and its beam and disc openings which corresponds to the thickness of the metal. As a consequence, during the bending of the metal, the clamping beam can retreat a distance equal to the metal thickness, this retreating being from the position of the beam in Fig. 3 to that of Fig. 4. As a result, the bends made are accurate and sharp and there is no stretching or tearing of the metal.

A number of the advantages of the brake described above will be readily appreciated. It is both light and inexpensive to manufacture. By the use of the particular cam mechanism, the bends can be made quickly and during the bending the cam pressure will be distributed evenly so as to improve the rigidity of the beam. Also, the cam discs protect the clamping bolts against being bent by the great force which must be exerted to bow the beam over the fulcrum members. Further, an open-end brake is provided which permits a number of bends not possible on a closed-end type, one such commonly required bend being the bending of one portion of a length of sheet while the remaining portion is left unbent. For example, it may be desired to bend up both end portions of a sheet and leave the central portion lying in a plane of the sheet as a tongue member. To do so the sheet first is slit twice to divide the portions to be bent from the central tongue and then the right-hand portion bent in the left-hand open end of the machine and the left-hand portion in the right-hand end.

An important additional advantage and feature of the invention is that, if desired, the open-end brake is quickly and easily convertible into a closed-end brake of the type having the improvements of the brake shown and described in my copending application, Serial No. 763,815, filed July 26, 1947. This conversion is desirable when lengths of metal must be bent which are longer than the space between the bolts and the clamping beam ends are required. Aside from the fulcrum blocks of the present invention, the principal difference in the close-end brake of this former application is that its beam is secured at its ends to the bedplate. The securing means, preferably, are threaded bolts similar to bolts 21 and are part of cam mechanisms substantially the same as that described above. Also the closed-end beam carries downward projections to rock its beveled edge into clamping engagement with the metal.

The present open-end brake is adapted for ready conversion simply by forming a pair of openings 41 and 42 in each end of its bedplate. Openings 41 are sized to receive the beam securing bolts and openings 42 to receive coil springs, or the like, to raise the beam from the bedplate. Conversion is made simply by removing the open-end clamping beam by unscrewing its bolts 21, and then substituting the closed-end beam by screwing its bolts into openings 41 at the beam ends.

According to the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

40 I claim:

1. An open-ended sheet metal bending brake comprising a bedplate, a clamping beam having a beveled working edge, clamping beam lifting means for raising said beam clear of said plate to permit insertion of metal therebetween, cam mechanism for pressing said beam downwardly against said plate and clamping said inserted metal, said mechanism including a beam securing member anchored in said bedplate and projecting vertically upwardly through an enlarged opening provided in the central portion of said clamping beam whereby a substantial length of said beam projects outwardly of said securing member, and a fulcrum member disposed between said beam and bedplate and spaced inwardly of said beam securing member, downward pressure on said beam initially moving its beveled edge into contact with said inserted metal and then forcefully pressing the metal clamping length of the beam into metal clamping engagement, said force causing said beam to bow about said fulcrum member whereby sufficient strength is imparted to the bowed end to firmly clamp the metal during a bending operation.
- 65 2. An open-ended sheet metal bending brake comprising a bedplate, a clamping beam having a beveled working edge, clamping beam lifting means for raising said beam clear of said plate to permit insertion of metal therebetween, cam mechanism for pressing said clamping beam downwardly against said plate and clamping said inserted metal, said mechanism including a beam securing member anchored in said bedplate and projecting vertically upwardly through the central portion of said clamping beam whereby a

substantial length of said beam projects outwardly of said securing member, said member mounting a pair of slidably contacted discs and being reciprocable with respect to said beam and discs, said discs operating to evenly distribute the cam pressure to the clamping beam to absorb bending forces acting on said member, and a fulcrum member disposed between said beam and bedplate and spaced inwardly of said beam securing member, downward pressure on said beam initially moving its beveled edge into contact with said inserted metal and then forcefully pressing the metal clamping length of the beam into metal clamping engagement, said pressure causing said beam to bow about said fulcrum member whereby sufficient strength is imparted to the bowed beam to firmly clamp the metal during a bending operation.

3. An open-ended sheet metal bending brake comprising a bedplate, a rockable clamping beam carried by said plate and having a beveled front edge, clamping beam lifting means for raising said beam clear of said plate to permit insertion of metal therebetween, a pair of cam mechanisms for pressing said beam downwardly against said plate and clamping said inserted metal, each of said pair including a beam securing member anchored in said bedplate and projecting upwardly through an opening provided in said clamping beam a relatively short distance from its center, said member mounting a pair of slidably contacted discs and being reciprocable with respect to said beam and discs, said discs operating during the rocking of the beam and the bending of the metal to absorb forces tending to bend the securing member and to evenly distribute the cam pressure to the clamping beam, and a fulcrum member disposed between said beam and bedplate and spaced inwardly of said beam securing members, said fulcrum member contacting said plate when said beam is cam pressed downwardly and causing said beveled edge of the beam both to rock forwardly into contact with said inserted metal, further cam pressure then forcing the metal clamping length of said beveled edge into metal clamping engagement, said further pressure causing said beam to bow about said fulcrum member whereby sufficient strength is imparted to the bowed beam to firmly clamp the metal during a bending operation.

4. An open-ended sheet metal bending brake comprising a bedplate, a rockable clamping beam carried by said plate and having a beveled front edge, clamping beam lifting means for raising said beam clear of said plate to permit insertion of metal therebetween, a pair of cam mechanisms for pressing said beam downwardly against said plate and clamping said inserted metal, each of said pair including a beam securing member anchored in said bedplate and projecting upwardly through an opening provided in said clamping beam a relatively short distance from its center, said member mounting a pair of slidably contacted discs and being reciprocable with respect to said beam and discs, said discs operating during the rocking of the beam to absorb forces tending to bend the securing member and to evenly distribute the cam pressure to the clamping beam, and a fulcrum block for each of said pair of cam mechanisms, each of said blocks projecting downwardly from said clamping beam and being disposed a set distance inwardly from each of said beam securing members, said downward projections contacting said plate when said beam is cam-pressed downwardly and causing said

beveled edge of the beam to rock forwardly into contact with said inserted metal, further cam pressure then forcing the metal clamping length of said beveled edge into metal clamping engagement, said further pressure causing said beam to bow about a fulcrum member whereby sufficient strength is imparted to the bowed beam to firmly clamp the metal during a bending operation.

5. An open-ended sheet metal bending brake comprising a bedplate, an arched clamping beam having a beveled working edge, clamping beam lifting means for raising said beam clear of said plate to permit insertion of metal therebetween, cam mechanism for pressing said beam downwardly against said plate and clamping said inserted metal, said mechanism including a beam securing member anchored in said bedplate and projecting vertically upwardly through an enlarged opening provided in the central portion of said clamping beam whereby a substantial length of said beam projects outwardly of said securing member, and a fulcrum member disposed between said beam and bedplate and spaced inwardly of said beam securing member, downward pressure on said beam initially moving its beveled edge into contact with said inserted metal and then forcefully pressing the metal clamping length of the beam into metal clamping engagement, said force causing said beam to bow about said fulcrum member whereby sufficient strength is imparted to the bowed end to firmly clamp the metal during a bending operation.

6. An open-ended sheet metal bending brake comprising a bedplate, a rockable arched clamping beam carried by said plate and having a beveled front edge, clamping beam lifting means for raising said beam clear of said plate to permit insertion of metal therebetween, a pair of cam mechanisms for pressing said beam downwardly against said plate and clamping said inserted metal, each of said pair including a beam securing member anchored in said bedplate and projecting upwardly through an opening provided in said clamping beam a relatively short distance from its center, said member mounting a pair of discs slidably contacting and being reciprocable with respect to said beam and discs, said discs operating during the rocking of the beam and the bending of the metal to absorb forces tending to bend the securing member and to evenly distribute the cam pressure to the clamping beam, a fulcrum member disposed between said beam and bedplate and spaced inwardly of said beam securing members, said fulcrum member contacting said plate when said beam is cam pressed downwardly and causing said beveled edge of the beam to rock forwardly into contact with said inserted metal, further cam pressure then forcing the metal clamping length of said beveled edge into metal clamping engagement, said further pressure causing said beam to bow about said fulcrum member whereby sufficient strength is imparted to the bowed beam to firmly clamp the metal during a bending operation.

7. An open-ended sheet metal bending brake comprising a bedplate, a rockable clamping beam carried by said plate and having a beveled front edge, clamping beam lifting means for raising said beam clear of said plate to permit insertion of metal therebetween, a pair of cam mechanisms for pressing said beam downwardly against said plate and clamping said inserted metal, each of said pair including a beam securing member anchored in said bedplate and projecting upwardly through an opening provided in said

clamping beam a relatively short distance from its center, said member mounting a pair of slidably contacting discs for distributing cam pressure and absorbing forces tending to bend said securing member, said discs and clamping beam being provided with securing member receiving openings of greater diameter than said member for permitting said beam to be selectively positioned on said plate with regard to the gauge metal being bent, means for moving said beam into said selected position, and a fulcrum member disposed between said beam and bedplate and spaced inwardly of said beam securing members, said fulcrum member contacting said plate when said beam is cam pressed downwardly and causing said beveled edge of the beam to rock forwardly into contact with said inserted metal, further cam pressure then forcing the metal clamping length of said beveled edge into metal clamping engagement, said further pressure causing said beam to bow about said fulcrum member whereby sufficient strength is imparted to the bowed beam to firmly clamp said metal during a bending operation.

8. An open-ended sheet metal bending brake comprising a bedplate, a rockable clamping beam carried by said plate and having a beveled front edge, clamping beam lifting means for raising said beam clear of said plate to permit insertion of metal therebetween, a pair of cam mechanisms for pressing said beam downwardly against said plate and clamping said inserted metal, each of said pair including a beam securing member anchored in said bedplate and projecting upwardly through an opening provided in said clamping beam a relatively short distance from its center, said member mounting a pair of slidably contacting discs for distributing cam pressure and absorbing forces tending to bend said securing member, said discs and clamping beam being provided with securing member receiving openings of greater diameter than said member for permitting said beam to be selectively positioned on said plate with regard to the gauge metal being bent, a pair of beam-positioning set screws for each of said cam mechanisms, said screws of each pair extending transversely through said clamping beam into contact with opposite sides of said securing member and operating to move the beam into said selected position, and a fulcrum member disposed between said beam and bedplate and spaced inwardly of said beam securing members, said fulcrum member contacting said plate when said beam is cam pressed downwardly and causing said beveled edge of the beam to rock forwardly into con-

tact with said inserted metal, further cam pressure then forcing the metal clamping length of said beveled edge into metal clamping engagement, said further pressure causing said beam to bow about said fulcrum member whereby sufficient strength is imparted to the bowed beam to firmly clamp said metal during a bending operation.

9. An open-ended sheet metal bending brake comprising a bedplate, a clamping beam having a beveled working edge, clamping beam lifting means for raising said beam clear of said plate to permit insertion of metal therebetween, cam mechanism for pressing said beam downwardly against said plate and clamping said inserted metal, said mechanism including a threaded bolt anchored in said bedplate and projecting vertically upwardly through an enlarged opening provided in the central portion of said clamping beam whereby a substantial length of said beam projects outwardly beyond said securing member, and a fulcrum member disposed between said beam and bedplate and spaced inwardly of said threaded bolt, downward pressure on said beam initially moving its beveled edge into contact with said inserted metal and then forcefully pressing the metal clamping length of the beam into metal clamping engagement, said force causing said beam to bow about said fulcrum member whereby sufficient strength is imparted to the bowed end to firmly clamp the metal during a bending operation, said beam being provided at each end with a threaded opening for receiving beam securing bolts of an alternatively usable closed-end brake beam.
